UNITED STATES PATENT OFFICE

2,434,721

SPRAY NOZZLE

Arthur C. Rowley, Drexel Hill, Pa., assignor to
 Globe Automatic Sprinkler Company, Philadelphia, Pa., a corporation of Pennsylvania

Application February 25, 1946, Serial No. 649,817

5 Claims. (Cl. 299—115)

1

This invention relates to new and useful improvements in spray nozzles, and more particularly to spray nozzles for automatic sprinkler and like systems.

It is known that fires in general, and certain types of fires in particular, may be more effectively combatted and extinguished by the use of water in the form of a fog or very finely divided spray than by the use of the conventional type spray of a number of small streams of water, and the principal object of the present invention is to provide a novel and improved nozzle which is constructed and arranged to produce an extremely finely divided spray or fog.

Another object of the invention is to provide a nozzle of the character set forth which may be employed effectively in automatic sprinkler systems and like installations.

A further object of the invention is to provide a novel and improved spray nozzle having the described features and characteristics which are of comparatively simplified and inexpensive construction and highly efficient and foolproof in operation and use.

These and other objects of the invention, and the various features and details of the construction and operation thereof, are hereinafter fully set forth and described with reference to the accompanying drawing, in which:

Fig. 1 is a plan view of the discharge end of a nozzle made according to the present invention.

Fig. 2 is an elevational view of the nozzle disclosed in Fig. 1.

Fig. 3 is an enlarged sectional view taken on line 3—3, Fig. 1.

Fig. 4 is a sectional view taken on line 4—4, Fig. 3; and

Fig. 5 is an enlarged fragmentary sectional view taken on line 5—5, Fig. 1.

Referring now to the drawing, a spray nozzle made according to the present invention is generally designated by reference numeral 1 and comprises a body 2 and a discharge tip 3. The body 2 includes inlet and outlet portions 4 and 5, respectively, between which there is provided an enlarged general spherical or bulbous portion 6. The discharge tip 3 is provided with an externally threaded skirt portion 7 of reduced diameter which is screwed inwardly of the end of the outlet portion 5 of the body 2 as shown, and a suitable gasket 8 is interposed between the adjacent annular faces of the body 2 and tip 3 to provide a fluid-tight joint therebetween.

In the illustrated embodiment of the invention, the inlet portion 4 of the body 2 may be ex-

2

ternally threaded at its end as indicated at 9 for connection, for example, to the outlet pipe 10 of a conventional sprinkler system. The inlet portion 4 also may be provided on its exterior with a hexagonal or similar portion 11 adapted to receive a wrench or the like which may be employed to connect or disconnect the nozzle 1 from the pipe 10.

At its inner end the inlet portion 4 of the body 10 2 opens into a generally spherical chamber 12 which is contained within and defined by the enlarged bulbous body portion 6, and formed integrally with the body 2 and extending inwardly of this chamber 12 from the outlet side thereof is a partition structure comprising a cylindrical wall portion 13 which terminates in a transverse end wall portion 14 that is disposed substantially centrally and crosswise of the chamber 12. Extending from this transverse end wall portion 14 coaxially of the body 2 through and beyond the outlet portion 5 thereof to a point adjacent the end of the discharge tip 3 is a generally conically shaped portion 15 which, together with the end wall 14, the cylindrical wall 13 and the outlet end portion 5 of the body 2, forms and defines within said body 2 an annular passage 16 which extends from the chamber 12 through the outlet portion 5 substantially to the discharge tip 3.

Communication from the chamber 12 to the annular passage 16 is provided by means of ports or openings 17 and 18, respectively, formed in the wall portion 13 at diametrically opposite sides thereof and adjacent the transverse end wall 14. These ports 17 and 18 are arranged as shown in Fig. 4 of the drawing so that water or other liquid passing therethrough from the chamber 12 into the annular passage 16 enters the latter in a direction substantially tangent thereto.

As best shown in Fig. 5 of the drawing, the outer end of the conically shaped portion 15 is provided with a radially extending flange portion 19, and the end face of said conical member 15 is counterbored as shown to provide therein a coaxial conical recess 20. A plurality of longitudinally extending ports or passages 21 are provided through the flanged and recessed end portion of the conical member 15 and these passages 21 are arranged circumferentially with respect to the member 15 at equally spaced intervals.

The end of the discharge tip 3 which lies in outwardly spaced relation with respect to the end of the conical member 15 is provided with a coaxial discharge opening 22 constructed and arranged, for example, as shown in the drawing and

the diameter of this discharge opening 22 and the arrangement of the ports or passages 21 in the flanged outer end of the conical member 15 are such that the said several ports or passages 21 have their axes substantially in alignment with the inner edge 23 of the discharge opening 22 through the tip 3.

In operation of a spray nozzle constructed as herein described, water or other liquid under pressure enters the chamber 12 of the body 2 through the inlet portion 4 thereof from the pipe 13, and then enters the annular passage 16 through the openings 17 and 18 in the wall 13. Since the openings 17 and 18 are disposed tangent to the passage 16, water or other liquid entering the latter is caused to traverse a spiral path of movement outwardly through the passage 16 toward the discharge end of the nozzle 1. As the water or other liquid reaches the end of the conical member 15, part thereof will pass through the ports or passages 21 in the outer end of the member 15 while the remainder will pass about the outside of the flange 19 and then inwardly to the discharge orifice 22 of the tip 3 between the end face of said flange 19 and the adjacent inner wall of the tip 3.

Since the water or other liquid supplied to the nozzle 1 is under pressure, the ports or passages 21 in the flanged end portion of the conical member 15 function in the manner of jets or orifices to discharge the water passing therethrough at high velocity, and as these ports or passages 21 have their axes disposed substantially in alignment with the inner edge 23 of the tip discharge opening 22, the jets of liquid discharging outwardly from the passages 21 at high velocity serve to impinge the water passing about the exterior of the flange 19 against the sharp inner edge 23 of the tip discharge opening 22 with the result that the water is broken up into very finely divided particles which discharge from the nozzle through the opening 23 in the form of a very finely divided spray of the nature of a heavy fog or mist.

From the foregoing description it will be apparent that the present invention provides a novel and improved nozzle which is operable to produce an extremely finely divided spray or fog. In addition, the invention provides a nozzle of the fog-producing type which may be employed effectively in automatic sprinkler systems and like installations and which is of comparatively simplified and inexpensive construction that is highly efficient and foolproof in operation and use.

While a particular embodiment of the invention has been illustrated and described herein it is not intended to limit the invention to such disclosure and changes and modifications may be made therein and thereto within the scope of the claims.

I claim:

1. A nozzle of the type described comprising a body having an inlet and an outlet and an intermediate chamber in open communication with said inlet, a discharge tip at the end of said outlet having a discharge port therein, and means in said body providing an annular passage from said chamber through said outlet substantially to said discharge tip, said means having ports therein opening from said chamber to said annular passage substantially tangent thereto and having a plurality of discharge openings therein adjacent said discharge tip arranged with their

axes substantially in alignment with the adjacent edge of the discharge port in said tip.

2. A nozzle of the type described comprising a body having coaxial inlet and outlet portions and an intermediate portion defining a chamber in open communication with said inlet portion, a discharge tip associated with said outlet portion and having a discharge port therein coaxially of the body, and means in said body providing an axially concentric annular passage from said chamber through said outlet portion substantially to said discharge tip, said means having ports therein opening from said chamber to said annular passage substantially tangent thereto and having adjacent said discharge tip a plurality of axially extending discharge openings disposed in arrangement corresponding to the configuration of the discharge port of said tip with their axes substantially in alignment with the adjacent edge of said discharge port in the tip.

3. A nozzle of the type described comprising a body member having an inlet and an outlet and an intermediate chamber in open communication with said inlet, a discharge tip at the outlet of said body having a discharge port therein, a partition extending inwardly of said chamber from the outlet side thereof, a member extending from said partition outwardly through the outlet portion of said body substantially to said discharge tip, said partition having ports therein opening from said chamber to said annular passage substantially tangent thereto, and said member having in its outer end a plurality of axially extending discharge openings arranged with their axes substantially in alignment with the adjacent edge of the discharge port in said tip.

4. A nozzle of the type described comprising a body member having an inlet and an outlet and an intermediate chamber in open communication with said inlet, a discharge tip at the outlet of said body having a discharge port therein, a side wall extending inwardly of said chamber from the outlet side thereof and terminating in an end wall arranged transversely of said chamber, a member extending from said end wall outwardly through the outlet of said body, said side and end walls and said member providing in said body an annular passage from said chamber substantially to said discharge tip, said side wall having ports therein opening from said chamber to said annular passage substantially tangent thereto, and said member having in its outer end a plurality of axially extending discharge openings arranged with their axes substantially in alignment with the adjacent edge of the discharge port in said tip.

5. A nozzle of the type described comprising a body member having coaxial inlet and outlet portions and an intermediate portion defining a chamber in open communication with said inlet portion, a cylindrical wall extending inwardly of said chamber from the outlet side thereof and terminating in an end wall arranged transversely of said chamber, an outwardly tapered member extending coaxially of the body from said end wall through the outlet portion of said body, said cylindrical and end walls and said tapered member defining within the body an annular passage, said cylindrical wall having ports therein at diametrically opposite sides thereof adjacent said end wall and opening from said chamber to said annular passage substantially tangent thereto, a

flange at the outer end of said tapered member, said flanged outer end of said tapered member having therein a plurality of axially extending discharge ports arranged thereabout at equally spaced intervals, and a discharge tip secured to the outlet portion of said body having a coaxial discharge port therein, the discharge port in said tip having its edge spaced outwardly from the flanged end of said tapered member and substantially in alignment with the axes of the axial discharge ports therein.
